TOY RACE COURSE DEVICE

Filed Dec. 14, 1925

Inventor
Fred L. Mills,
By his son, Fred L. Mills,
Attest,

UNITED STATES PATENT OFFICE.

FRED L. MILLS, OF OAK PARK, ILLINOIS, ASSIGNOR TO MILLS NOVELTY COMPANY, OF CHICAGO, ILLINOIS, A CORPORATION OF ILLINOIS.

TOY RACE-COURSE DEVICE.

Application filed December 14, 1925. Serial No. 75,347.

To all whom it may concern:

Be it known that I, FRED L. MILLS, a citizen of the United States, residing at Oak Park, in the county of Cook and State of Illinois, have invented a new and useful Improvement in Toy Race-Course Devices, of which the following is a specification.

This invention relates particularly to means for readily changing the permutation in a toy race course of the character described in my Patent No. 1,559,120, issued Oct. 27, 1925.

The invention pertains particularly to the permutation-belt employed in a race course of the character described in the above-mentioned patent, and in the combinations hereinafter set forth. The invention is illustrated in the accompanying drawing, in which—

Fig. 1 represents a broken elevational view of a toy race course constructed in accordance with the invention; Fig. 2, a broken plan view of the permutation-belt and a racer-positioning belt employed; Fig. 3, a broken plan view on a greatly enlarged scale, showing a fragment of the permutation-belt equipped with an improved catch-device which serves as a racer-actuating member; Fig. 4, a sectional view taken as indicated at line 4 of Fig. 3; and Fig. 5, a still more greatly enlarged sectional view taken as indicated at line 5 of Fig. 4.

The drawing illustrates a toy race course of the general construction and mode of operation set forth in the above-mentioned application. To enable the present invention to be understood, it is unnecessary to fully illustrate the apparatus described in said patent.

In the drawing, A designates a series of endless race tracks disposed in parallel vertical planes, the front one of said tracks being shown brokenly in Fig. 1; B designates a permutation-belt mounted on shafts 1 and 2; C designates a racer-positioning belt mounted on shafts 3 and 4; D designates a series of racers mounted on the parallel race tracks; and E designates a portion of a suitable cabinet containing the apparatus, the front side of the cabinet being provided with a view-opening, or window, E'.

The shaft 2 is actuated in any suitable manner, preferably by means of an electric motor which is suitably controlled and which will serve to move the racers through

the circuit and then come to a stop, if desired. The shaft 2 is connected by means of a belt 5 with the shaft 4, and thus serves to drive the racer-positioning belt C. A magnet-controlled clutch 6 controls the operation of the belt 5. The clutch 6 may, in turn, be controlled by an electric circuit, which electric circuit may be controlled by means of a note-producing device of a musical instrument. Such a device is described in the patent mentioned above. The cabinet E may comprise the cabinet of the musical instrument which controls the operation of the clutch 6.

The permutation-belt B is provided with any desired number of racer-actuating devices B'. The devices B' may be of the construction illustrated in Figs. 3-5.

The racer-positioning belt C is equipped with a cross-member 7 which is adapted to engage the catch-members with which the racers D are equipped. This action occurs after the racers have passed beyond the field of vision indicated by the window E', at which time the racers are also beyond the range of action of the permutation-belt. The racer-positioning belt serves to engage the racers and return them to the initial end of the course, which appears at the right hand portion of Fig. 1.

A portion of an electric circuit is shown in Fig. 1 and is designated 8. It is, however, unnecessary to fully illustrate and describe the electric circuits employed. Each of the racers D is provided with a depending catch-member 9 which is adapted to be engaged by one of the catch-members, or racer-actuating members, B'. The members 9 may be of any suitable construction. They may be, for example, of the construction described in the above-mentioned patent.

The catch-members 9 with which the racers are equipped are adapted to be engaged also by the member 7 of the permutation-belt C after the racers have passed beyond the range of action of the permutation-belt. The racer-positioning belt then serves to return the racers to the initial end of the course and bring them again within the range of action of the permutation-belt. It will be noted that the upper and lower reaches of the endless tracks A are joined by semi-circular end-portions 10.

The purpose of the improved racer-actuat-

ing members B' with which the permutation-belt is equipped is to enable the permutation to be changed readily at will. Each member B' preferably comprises a transversely disposed angle bar 11 secured to the permutation-belt by means of rivets 11^a; and a catch-member 12 adjustably mounted on the bar 11, so that the catch-member can be so positioned as to be located in the vertical plane of any one of the race tracks. By employing a suitable number of transverse bars and shiftably mounted catch-members supported thereon, it is possible readily to effect different combinations of the catch-members and thus affect the sequence in which the racers are carried forward by the permutation-belt during the race.

The angle-bar 11 is shown mounted on a reinforcing bar 13 which is interposed between the belt and the base-portion of the angle-bar 11. The catch-member 12 is of angle form having a horizontal arm 12^a and a vertical arm 12^b. The arm 12^a is equipped at its rear edge with a depending catch-lug 12^c which may engage any one of a series of notches, or recesses, 14, with which the horizontal flange of the member 11 is equipped. The vertical flange of the member 11 is provided with an elongated slot 11^b which accommodates a stud 15 which has its rear end riveted at 15^a to the base-portion of the arm 12^b. A coil-spring 16 is interposed between the head 15^b of the stud and a washer 17 which bears against the front surface of the vertical flange of the angle-bar 11. The spring holds the member 12 in contact with the vertical flange of the angle-bar 11 and holds the lug 12 in engagement with one of the notches 14. By pressing rearwardly on the stud 15, the lug 12^c may be disengaged from the notch and the catch-member 12 may then be shifted to a new position and allowed to interlockingly engage another notch. The notches 14 are so disposed that they will lie in the planes of the parallel race tracks; and when the catch-member 12 is set in proper position it will be disposed beneath the upper reach of one of the race tracks.

The catch-members 12 on the several cross bars, or mounting bars, may be arranged in staggered relation with respect to each other, or in any desired relation, to effect the desired sequence of the racers. By positioning a greater number of catch-members in the plane of one racer than in the plane of another racer, the percentage of changes of the favored racer may be increased.

The operation of the apparatus as a whole is the same as that described in the above-mentioned application and may be briefly stated here. The racers may be assumed to start from about the position shown in Fig. 1 and to return to about the same position in a cycle of operations, it being understood,

however, that the sequence of the racers may vary, owing to the operation of the apparatus. The permutation-belt, in the illustration given, travels more rapidly than the racer-positioning belt. As indicated, the operation of a suitable motor for driving the apparatus may be controlled by means of a coin, if desired. In the operation, the racer-actuators engage the depending projections 9 of the racers and move the racers along the upper reach of the race tracks until the racers are carried beyond the range of action of the permutation-belt. The racers are then left in transverse alignment at the final end of the permutation-belt and presently are engaged by the member 7 of the racer-positioning belt C. The member 7 engages the catches 9 of all the racers, and returns the racers to the initial end of the race course and brings them within the range of action of the permutation-belt.

By reason of the difference in the speed of the two belts, a change in the sequence of the racers will occur when the racers are brought again in the range of action of the permutation-belt at the initial end thereof. Also, as explained in the above-mentioned application, means may be provided for automatically changing the relative movements of the two belts at regular or irregular intervals. For example, said application describes means whereby the clutch 6, shown in the accompanying drawing, may be released when a certain note of the musical instrument is struck, thus permitting the racer-positioning belt C to stop momentarily, so that the relative movements of the two belts are thus varied. This results in a still further variation of the sequence of the racers.

It may be added that the plane of the shafts 3 and 4 is below the plane of the shafts 1 and 2, so that while the racers are being returned to the initial end of the course the racer-actuators B' will not engage the racers.

The foregoing detailed description has been given for clearness of understanding only and no unnecessary limitations should be understood therefrom, but the appended claims should be construed as broadly as permissible in view of the prior art.

What I regard as new, and desire to secure by Letters Patent, is:

1. In a device of the character set forth, a series of independently movable racers, and a permutation-belt equipped with variable racer-actuators, each comprising a mounting member carried by the belt and an actuating member carried by said mounting member and adjustable crosswise of the belt.
2. In a device of the character set forth, a series of parallel race tracks disposed in vertical planes, racers mounted on said tracks, a permutation-belt, a series of mount-

ings on said belt disposed crosswise of the belt, and catch-members carried by said mountings, each catch-member being adjustable on its mounting and capable of being 5 shifted to a position to engage one race member or another at will.

3. A permutation-belt for the purpose set forth equipped with a plurality of transversely disposed bars, and catch-members 10 mounted on said bars and adjustable thereon transversely of the belt.

4. A permutation-belt for the purpose set forth equipped with a plurality of transversely disposed bars provided with slots, a 15 catch-member mounted on each bar and equipped with a stud extending through said

slot, and a spring mounted on said stud and serving to hold the catch-member in position with relation to the bar.

5. A permutation-belt equipped with a 20 plurality of transverse angle-bars having vertical flanges provided with slots and horizontal flanges secured to the belt; an angle-form catch-member slideable on each bar and equipped with a lug adapted to engage recesses with which the horizontal flange of the angle-bar is provided, a stud secured to the vertical arm of the catch-member and movable in said slot, and a spring confined between said stud and the vertical flange of 25 the angle-bar, for the purpose set forth. 30

FRED L. MILLS.
